UNITED STATES PATENT OFFICE

EDMUND L. DAY, OF WESTLINE, PENNSYLVANIA

DESTRUCTIVE DISTILLATION APPARATUS

Application filed December 17, 1928. Serial No. 326,590.

This invention relates to stills of that type used in practicing destructive distillation processes, and has for one of its objects to provide a novel apparatus of this character which shall be adapted to permit large quantities of wood, charcoal, oil, tar and other materials to be fractionally distilled in an economical and highly efficient manner.

The invention has for a further object to provide an apparatus of the character stated which will function in a manner to provide a distillate containing comparatively little foreign matter.

The invention has for a further object to provide an apparatus of the character stated which shall embody a plurality of fractionating units adapted to successively act upon the vapor during its passage through the still to remove therefrom all heavy or high boiling point components, whereby to provide a distillate containing comparatively little foreign matter.

The invention has for a further object to provide an apparatus of the character stated wherein the fractionating units shall be arranged within the still in a manner to effect the removal of the high boiling point components from the vapor at progressively lower temperatures.

The invention has for a further object to provide an apparatus of the character stated wherein one of the fractionating units shall be arranged within a retort and the remainder within a column receiving the vapor from the retort, the components separated out of the vapor by said first unit remaining in the retort for further distillation.

The invention has for a further object to provide an apparatus of the character stated wherein certain of the components separated out of the vapor in the column shall be precipitated into the retort for further distillation, and wherein the remaining components separated out of the vapor in the column shall be directed to receptacles from which they may be drawn off without opening the column.

The invention has for a further object to provide an apparatus of the character stated wherein the column shall be of substantially

T-form presenting a vertical column member and a horizontal column member, the vertical column member having upper and lower compartments, and the horizontal column member having upper and lower compartments communicating with each other and with the respective compartments of the vertical column member.

The invention has for a further object to provide an apparatus of the character stated wherein a fractionating unit shall be arranged in each compartment of the column.

The invention has for a further object to provide an apparatus of the character stated wherein the vertical column member shall be provided with a downwardly directed discharge passage to facilitate the separation of the high boiling point components from the vapor.

The invention has for a further object to provide an apparatus of the character stated wherein the fractionating unit within the retort shall be in the form of a cartridge adapted to be readily placed within and removed from the retort.

The invention has for a still further object to provide an apparatus of the character stated which shall embody means adapted to cooperate with means on the cartridge to insure the passage of all the vapor through the cartridge.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view in front elevation of the still;

Figure 2 is a sectional view on an enlarged scale taken on the vertical plane indicated by the line 2-2 of Figure 1;

Figure 3 is a sectional view taken on the vertical plane indicated by the line 3-3 of Figure 2;

Figure 4 is a sectional view taken on the horizontal plane indicated by the line 4-4 of Figure 2;

Figure 5 is a sectional view taken on a

plane extending vertically and centrally through the column of the still;

Figure 6 is a sectional view taken on the horizontal plane indicated by the line 6—6 of Figure 5;

Figure 7 is a sectional view taken on the vertical plane indicated by the line 7—7 of Figure 5;

Figure 8 is a detail sectional view illustrating the manner in which the doors of the retort are secured in place and the manner in which the doors are sealed to prevent the escape of any vapors from the retort;

Figure 9 is a view in side elevation of the column of the still illustrating a modified form of the means for maintaining the horizontal column member at the required temperature;

Figure 10 is a sectional view taken on the plane indicated by the line 10—10 of Figure 9, and

Figure 11 is a sectional view taken on the plane indicated by the line 11—11 of Figure 4.

Referring in detail to the drawings, 1 designates the retort of the still. This part is of substantially cylindrical formation, and is suspended by hangers 2 in a horizontal position within the combustion chamber 3 of a furnace 4 which may be of any well known or appropriate construction and of which 5 designates the fire door, 6 the ash door and 7 the discharge flue.

The front and rear doors 8 and 9, respectively, of the retort 1 are secured in place by apertured lugs 10 and wedges 11. The lugs 10 are carried by continuous flanges 12 which extend radially from the ends of the retort 1 and are provided in their outer faces with grooves 13 for the reception of packing rings 14. The doors 8 and 9 rest against the packing rings 14, and are provided with openings 15 for the passage of the lugs 10. The wedges 11 pass through the lugs 10 and contact with the outer faces of the doors 8 and 9. The lugs 10 and wedges 11 of each door 8 and 9 are, as shown in Figure 1, so relatively spaced as to permit the doors to be uniformly forced inwardly at all points and thus permit the packing rings 14 to be placed under such pressure as to establish a vapor tight connection between the doors and the retort 1.

The retort 1 embodies a material receiving chamber 1^a and a fractionating unit receiving member 1^b, the former being considerably longer than and arranged forwardly of the latter. The material is carried by wheel supported trucks 16, and the fractionating unit is in the form of a wheel supported cartridge 17. The trucks 16 and the cartridge 17 are mounted upon rails 18 so as to permit them to be readily moved into and out of the retort 1. The rails 18 extend longitudinally of and forwardly and rearwardly beyond the retort 1, and are provided at the front and rear ends of the retort with hinged or re-

movable sections 18^a and 18^b, respectively, which are adapted to be raised, as shown by solid lines in Figure 2, to permit the application and removal of the doors 8 and 9. Those portions of the rails 18 that are located within the retort 1 are secured to the bottom of the retort and terminate short of the ends thereof so as to permit the free ends of the rail sections 18^a to rest upon the bottom of the retort when the doors 8 and 9 are removed and these sections are in lowered position, as shown by broken lines in Figures 2 and 4. Those portions of the rails 18 that are located beyond the retort 1 are secured to ties 19 mounted upon the floor 20 of the building in which the still is located, the floor being located above the fire doors 5 of the furnace 4.

The cartridge 17 comprises a casing 21 which is fully open at its top and is provided in its lower side with a centrally arranged and longitudinally extending vapor intake passage 22. This passage is formed by an imperforate plate 23 arranged horizontally within and extending longitudinally of the casing 21 above the bottom thereof, and perforated plates or screens 24 extending from the side edges of the plate 23 to the bottom of the casing. The intake passage 22 is fully open at its front end which is in communication with the retort chamber 1^a, and it is of such formation as to cause the vapor to flow through every portion of the cartridge 17. The rear end of the intake passage 22 is closed by a clean out door 24^a which is hinged, as at 24^b, to the rear side of the casing 17.

The casing 21 is mounted upon and fixed to I-beams 25 which are in turn carried by the axles 26 of flanged wheels 27 and which are arranged inwardly of the wheels. The bottom flanges of the beams 25 bear lightly upon the rails 18, and are provided with openings for the passage of the lower portions of the wheels 27 so as to permit the wheels to rest upon the rails.

The bottom, lateral sides and top of the casing 21 are spaced from the corresponding parts of the retort chamber 1^b. A flange 28 which is of inverted U-form, is arranged at the front side of the casing 21 and extends beyond the lateral sides and top of the casing. A similar flange 29 is secured, as at 30, to the top and sides of the retort 1 at the juncture of the chambers 1^a and 1^b, and a packing 31 is arranged between this flange and the flange 28. The flange 28 is held under pressure in contact with the packing 31 by a screw 32 which is carried by the rear door 9, bears against the rear side of the casing 21 and is provided with a crank handle 33. A plate 34 which is hinged at its lower end, as at 34^a, in recesses 34^b formed in the upper sides of the rails 18, extends from the bottom walls of said recesses to a plane coincident with the

upper side of the bottom of the casing 17, and contacts with the rear side of the flange 29. The plate 34 is provided at its rear side with a packing strip 35 with which the front 5 side of the casing 21 contacts. The screw 32 also functions to hold the casing 21 under pressure in contact with the packing strip 35. The plate 34 is supported in upright position by the cartridge 17, and when the cartridge 10 is drawn from the retort it falls into the recesses 34^b. The plate may be easily raised when the cartridge is to be again moved into the retort 1. A packing 36 which may consist of sand or any other suitable 15 material, is arranged on the bottom of the retort chamber 1^b, and cooperates with the packings 31 and 35 to seal the cartridge 17 within its compartment 1^b in such manner as to insure the passage of all of the vapor up- 20 wardly through the cartridge on its way from the retort chamber 1^a to the outlet tube 37 of the retort 1. The cartridge 17 also comprises means which acts upon the vapor in a manner to separate its heavier or higher 25 boiling point and its lighter or lower boiling point components, the heavier components remaining in the retort for further distillation and the lighter components passing to and through the outlet 37. This means 30 which is designated 38 and is arranged within in the casing 17, may consist of any suitable divided substance such as broken brick, terra cotta material, baked clay or vitrified spirals such as are commonly used in acid distilla- 35 tion, marbles, charcoal, saw dust or other material screens or the like.

After passing through the outlet 37, the vapor flows into the column 38 which comprises a vertical member 39 and a horizontal 40 member 40, and is arranged above the retort 1 with the lower end of the member 39 in communication with the outlet 37. The column member 40 communicates with the column member 39 below the horizontal center 45 of the latter. A horizontal partition 41 is fixed within the column member 39 in substantial alinement with the horizontal center of the column member 40. A partition 42 is removably supported within the column 50 member 40 in a plane slightly above said center, and has one end resting upon the partition 41 and its other end spaced from the outer end of this column member. The partitions 41 and 42 cause the vapor, after pass- 55 ing a comparatively short distance through the column member 39, to enter the column member 40 and travel twice throughout the entire length thereof before re-entering the column member 39. The column member 39 is provided below and above the inner end 60 of the column member 40 with grates 43 and 44, respectively, which consists of baked clay I-beams 45. Fractionating units 46 and 47 are supported within the column member 39 65 by the grates 43 and 44, respectively. A fractionating unit 48 is arranged within the outer end portion of the column member 40, and has the outer end of the partition 42 embedded therein. This unit is maintained in place by screens 49 and 50 and the inner 70 end portion of the partition 42. The units 46, 47 and 48 may each be made up from any of the materials heretofore set forth, it being preferred, however, to make the unit 48 from charcoal. 75

During its passage through the column 38, the vapor will be first subjected to the action of the fractionating unit 46, then to the action of the fractionating unit 48 and then to the action of the fractionating unit 47, which successively act upon the vapor in a manner to separate its heavier and lighter components. The components precipitated by the fractionating unit 46 will fall into a receptacle 51 and be subjected to a further distillation. 80 The receptacle 51 is carried by the cartridge 17 in alinement with the discharge flue 37. The receptacle 51 is arranged centrally within the cartridge upon the wall 23 and is surrounded by the fractionating unit 38. If desired the receptacle 51 may be omitted, and these components permitted to fall into the fractionating unit 17. The components precipitated by the fractionating unit 48 will be retained within the lower chamber of the column member 40 by a dam 52 which extends across said chamber and is secured to the bottom thereof, as at 53. The bottom of the column member 40 is provided near the dam 52 with an opening 54 which communicates with a trap 55 provided with a drain cock 56. The components accumulating within the lower chamber of the column member 40 will be subjected to further distillation. 95

After passing through the outlet 37, the vapor flows into the column 38 which comprises a vertical member 39 and a horizontal member 40, and is arranged above the retort 1 with the lower end of the member 39 in communication with the outlet 37. The column member 40 communicates with the column member 39 below the horizontal center of the latter. A horizontal partition 41 is fixed within the column member 39 in substantial alinement with the horizontal center of the column member 40. A partition 42 is removably supported within the column member 40 in a plane slightly above said center, and has one end resting upon the partition 41 and its other end spaced from the outer end of this column member. The partitions 41 and 42 cause the vapor, after passing a comparatively short distance through the column member 39, to enter the column member 40 and travel twice throughout the entire length thereof before re-entering the column member 39. The column member 39 is provided below and above the inner end of the column member 40 with grates 43 and 44, respectively, which consists of baked clay I-beams 45. Fractionating units 46 and 47 are supported within the column member 39 by the grates 43 and 44, respectively. A fractionating unit 48 is arranged within the outer end portion of the column member 40, and has the outer end of the partition 42 embedded therein. This unit is maintained in place by screens 49 and 50 and the inner end portion of the partition 42. The units 46, 47 and 48 may each be made up from any of the materials heretofore set forth, it being preferred, however, to make the unit 48 from charcoal. 75

During its passage through the column 38, the vapor will be first subjected to the action of the fractionating unit 46, then to the action of the fractionating unit 48 and then to the action of the fractionating unit 47, which successively act upon the vapor in a manner to separate its heavier and lighter components. The components precipitated by the fractionating unit 46 will fall into a receptacle 51 and be subjected to a further distillation. 80 The receptacle 51 is carried by the cartridge 17 in alinement with the discharge flue 37. The receptacle 51 is arranged centrally within the cartridge upon the wall 23 and is surrounded by the fractionating unit 38. If desired the receptacle 51 may be omitted, and these components permitted to fall into the fractionating unit 17. The components precipitated by the fractionating unit 48 will be retained within the lower chamber of the column member 40 by a dam 52 which extends across said chamber and is secured to the bottom thereof, as at 53. The bottom of the column member 40 is provided near the dam 52 with an opening 54 which communicates with a trap 55 provided with a drain cock 56. The components accumulating within the lower chamber of the column member 40 will be subjected to further distillation. 95

The components precipitated by the fractionating unit 47 fall onto the partition 41 which is dished and provided with a discharge opening 57 to convey the precipitated components into a receptacle 58 secured to the under side of the partition. A pipe 59 extending downwardly from the partition 41 about the opening 57 enters the receptacle 58 to provide a seal. A drain pipe 60 extends from the receptacle 58 to a point beyond the column member 39, and is provided at its outer end with a drain cock 61 with which is associated a trap 62. 100

The upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 105

upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 110

upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 115

upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 120

upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 125

upper portion of the column member 39 is separated into a vertical up passage 39^a and a vertical down passage 39^b, which communicate at their upper ends near the upper end of the column member. These passages are formed by a vertical partition 63 which is of arcuate formation in horizontal section, and has its vertical edges contacting with and secured to the inner surface of this column member, and by a horizontal partition 63^a which extends from the lower end of the partition 63 to the adjacent wall of the column member to which it is secured. The vertical 130

column member 39 is provided with a discharge opening 64 which communicates with the lower end of the down passage 39^b and with which a condenser or a plurality of condensers in series, not shown, are connected. After passing through the fractionating unit 47, the vapor passes downwardly through the passage 39^b and through the discharge opening 64 into the condenser. The bottom of the down passage 39^b is provided with a discharge opening 39^c which communicates with a trap 39^d having a drain cock 39^e.

In order to maintain the column member 40 at the required temperature during the initial phase of the operation of the still, there is provided a burner 65 which may be of any well known or appropriate type for consuming oil or gas and which, if desired, may take the form of a small furnace or electric heater.

After the initial phase of the operation of the still, the column member 40 will be maintained at a temperature approximately equal to the boiling point of crude wood tar, and the means for accomplishing this may be of any suitable or well known construction. As shown, in Figures 1 and 5, this means may consist of a blower 66 provided with a drive pulley 66^a, a manifold 67 surrounding the outer end of the column member 40 and receiving air from the blower, and nozzles 68 extending inwardly from the manifold and surrounding the column member, the nozzles being adapted to direct the air from the manifold into contact with the outer surface of the column member. If desired the blower 66 may be driven directly by an electric motor, not shown, which will have its armature shaft secured directly to the shaft of the blower.

The outer end of the column member 40 is closed by a door 69 which is hinged, as at 70, and is secured in closed position by lugs 71 and wedges 72 similar to those hereinbefore described. A sealing gasket 73 is positioned between the door 69 and the column flange 74 to which the door is hinged and which carries the lugs 71. The partition 42 may be withdrawn from the column member 40 through the outer end of the latter, and it is supported within the column member by angle bars 75, as clearly shown in Figure 7.

The upper end of the column member 39 is closed by a door 76 which is hinged, as at 77, to a flanged collar 78 fixed to this end of this member. The door 76 is counterbalanced by a weight 79 which is secured thereto by a cable 80 passing over direction pulleys 81. The door 76 is secured in closed position by a lug 82 carried by the flange 78 and extending upwardly through an opening 83 in the door, and by a key 84 which passes through the lug and contacts with the upper side of the door. This key is of fragile nature so that it will break under a pressure that would tend to disrupt the column 38. In view there-

of, and as the door 76 is counterbalanced, it will swing open whenever the pressure in the column 38 exceeds a predetermined degree. A gasket 76^a is provided for this door. The wedges 72 may also be fragile so that the door 69 will also function as a safety door.

This still is adapted to be used for the purpose of recovering valuable by-products from wood, charcoal, oil, tar and the like materials. When wood, charcoal or the like material is to be treated it is placed upon the trucks 16, while when tar or the like material is to be treated it is arranged in tanks of the type shown in my copending application, filed the 17th day of December, 1928 and serially numbered 326,591. Attention is also invited to my copending application filed December 17, 1928, Ser. No. 326,592.

The means for maintaining the column member 40 at the stated temperature may, as shown in Figures 9 and 10, consist of a pipe 85 which extends along the upper side of this column member and is provided in its under side with discharge openings 86. The pipe 85 has one end closed, and is connected at its other end to a source of water by a pipe 87. The water flows in streams from the pipe 85 onto the upper half of the column member 40, and is conveyed away from the column member by troughs 88 which are secured to opposite sides of the column member and inclined downwardly in the direction of one end thereof.

The column member 39 will be maintained at a temperature approximately equal to the boiling point of acetic acid. The means for maintaining the column member 39 at this temperature may be of any well known or appropriate construction, and is shown as consisting of a water jacket 89 surrounding the upper end portion of the column member, and provided with a supply pipe 90 and a discharge pipe 91.

The upper end of the column member 39 and the outer end of the column 40 are provided with pyrometers 92 and 93, respectively.

From the foregoing description, taken in connection with the accompanying drawings, it will be understood that, immediately before its passage from the retort and several times during its passage through the column, the vapor will be subjected to the action of fractionating units and that these units function successively and at progressively reduced temperatures in the order in which the vapor passes therethrough, with the result that the vapor is fractionated within the still and there is produced as a distillate or acetic acid comparatively free from foreign matter. The products of this highly refined distillate are materially aided by providing the vertical column member with the downwardly extending outlet passage which communicates at its upper end with the upper end of the col-

umn member and at its lower end with the column outlet.

The apparatus is worked under a slight vacuum. It may be made of any desired size, and the retort and column thereof may be made from boiler, copper or other plate. If desired the trucks may, after the removal of the cartridge, be removed through the rear end of the retort. The retort and column are vapor tight, and the precipitated components or wood tar may be withdrawn from the traps and subjected to further distillation.

What I claim is:

1. A destructive distillation apparatus, comprising, a column having upper and lower vertical chambers, and upper and lower horizontal chambers, the upper vertical chamber being provided intermediate its ends with a discharge opening and provided with a passage extending from adjacent the upper end thereof to said opening, the horizontal chambers communicating at their outer ends and communicating at their inner ends with the vertical chambers, and fractionating units within the chambers.

2. A destructive distillation apparatus, comprising, a column having a vertical member provided with a discharge opening and a horizontal member communicating at one end with the vertical member, a partition extending across the vertical member in substantial alinement with the horizontal center of the horizontal member and provided with a discharge opening, a receptacle arranged below the partition and communicating therewith, a partition arranged within the horizontal member in substantial alinement with said center thereof and having its inner end resting on said first partition and its outer end spaced from the outer end of said member, a dam arranged within the horizontal member below the partition therein, a receptacle arranged at the bottom of the horizontal member and communicating therewith, fractionating units within the vertical member above and below the partition therein, and a fractionating unit within the horizontal member and having the outer end of the partition of said horizontal member embodied therein.

3. A destructive distillation apparatus, comprising, a substantially L-shaped column having its vertical member and its horizontal member separated into upper and lower compartments, the compartments of the horizontal member communicating with each other at their outer ends and having their inner ends communicating with the compartments of the vertical member, and a fractionating unit in the outer end portion of the horizontal member.

4. A destructive distillation apparatus, comprising, a column having upper and lower vertical chambers and upper and lower horizontal chambers, the upper and lower

horizontal chambers communicating with each other at their outer ends and having their inner ends in communication respectively with the upper and lower vertical chambers, the upper vertical chamber being provided with an outlet opening and a discharge passage extending from the upper end of the chamber to said opening.

In testimony whereof I affix my signature.
